E. S. ROE:

AIR GUN.

APPLICATION FILED NOV. 12, 1920.

Patented June 13, 1922.

2 SHEETS—SHEET 2.

UNITED STATES PATENT OFFICE.

ERNEST S. ROE, OF PLYMOUTH, MICHIGAN, ASSIGNEE TO MARKHAM AIR RIFLE COMPANY, OF PLYMOUTH, MICHIGAN, A CORPORATION OF MICHIGAN.

AIR GUN.

1,419,308.

Specification of Letters Patent. Patented June 13, 1922.

Application filed November 12, 1920. Serial No. 423,570.

To all whom it may concern:

Be it known that I, ERNEST S. ROE, a citizen of the United States of America, residing at Plymouth, in the county of Wayne 5 and State of Michigan, have invented certain new and useful Improvements in Air Guns, of which the following is a specification, reference being had therein to the accompanying drawings.

10 The invention relates to guns and refers more particularly to air guns or rifles. One of the objects of the invention is to provide an air gun of that type in which the gun is cocked by what is known as breaking-down 15 the barrel and to provide means for automatically sealing the joint between the abutment in the casing and the barrel when the latter is in shooting position, or in other words, in alignment with the casing.

20 Another object of the invention is to provide means cooperating with the pivot connecting the barrel and casing to hold the barrel and casing in shooting position. Further objects of the invention reside in the novel features 25 of construction and combinations and arrangements of parts as more fully herein-after set forth.

In the drawings:

Figure 1 is a side elevation of an air gun 30 embodying my invention;

Figure 2 is a longitudinal sectional elevation of a portion thereof showing the parts in shooting position;

Figure 3 is a similar view showing the 35 parts in broken-down position;

Figure 4 is a perspective view of the true barrel mechanism;

Figure 5 is a bottom plan view of a portion of the air gun;

40 Figure 6 is a bottom plan view of a sight.

1 represents the usual stock of the gun, and 2 the barrel section thereof. The stock is provided at its forward end with the casing 3 which forms the housing for the air 45 compression chamber 4, the plunger 5, the coil spring 6 for actuating the plunger in one direction, and the trigger mechanism 7, which may be of usual construction. 8 is a stationary abutment secured in the forward 50 end of the air compression chamber 4 and having the central aperture 9 therein for the passage of the air.

The barrel section 2 is pivoted to the for-

ward end of the casing 3 at 10 and the break-down movement of this barrel section about 55 the pivot 10 is utilized for compressing the coil spring 6 and cocking the air gun. As shown, the barrel section 2 has the depending side flanges 11 at its rear end and the casing 3 has the depending side 60 flanges 12, the adjacent ends of which are pivotally connected together at 10. 13 is a rod, preferably U-shaped, pivotally connected at its ends to the depending side flanges 11 of the barrel section 2 as at 65 14. The base 15 of this U-shaped rod extends through the parallel longitudinal slots 16 in the depending side flanges 12 of the casing and is adapted to engage the down-turned end 17 of the shank secured to the 70 plunger 5 for longitudinally moving the latter backward to compress the coil spring 6 upon the breaking-down movement of the barrel section. As shown in Figure 3, the barrel section is rotated downwardly and to 75 the rear with respect to the casing until the down-turned end 17 is engaged by the shoulder 18 of the trigger mechanism after which the barrel section is returned back to shooting position, when it is in alignment 80 with the casing.

When the barrel section and casing are in alignment, their adjacent ends contact so that it is impossible to swing the barrel section further. To align the axis of the barrel 85 section and casing in a vertical plane, the forward end of the casing is provided with the upper segmental portion 3' which overlaps and fits the barrel section.

For the purpose of maintaining this barrel section in horizontal alignment with the casing, the U-shaped rod 13 is made resilient and its parallel arms extend adjacent to the outer sides of the depending side flanges 11 and also the pivot 14 is located upon the depending side flanges 11, so that when the barrel section is in alignment with the casing, the parallel arms of the U-shaped rod engage the heads at the opposite ends of the pivot 10 and those portions thereof adjacent 100 to the casing. Thus it is seen, that in order to break-down the air gun, the parallel arms of the U-shaped rod must yieldably bend laterally outward to pass over the heads of the pivot 10 and upon the return movement 105 of the barrel section, these parallel arms will

snap over these heads, thereby yieldably holding the barrel section and the casing in shooting position.

For the purpose of maintaining an air tight seal between the abutment 8 and the true barrel 19 and at the same time removably mounting the true barrel in the false barrel 20, the following construction is provided: 21 is a stop within the false barrel 20, 5 and 22 is an annulus surrounding the true barrel 19 and engaging the inner end of the stop 21. 23 is an abutment fixedly secured to the true barrel 19, and 24 is a coil spring between the annulus 22 and abutment 23, 10 for yieldably forcing the true barrel 19 rearwardly and into engagement with the abutment 8 in the casing 3. To limit the rearward movement of the true barrel 19 so that it will not become completely disengaged 15 from the false barrel 20 or moved rearwardly so far that it will interfere with the swinging of the barrel section into shooting position, there is the stop 25, which is preferably a sight, and has the portion 26 extending 20 forwardly within and parallel to the wall of the false barrel 20. The forward end of this portion of the stop has the U-shaped notch 27 therein for engagement by the abutment 23. Thus it is seen that the rear 25 end of the true barrel 19 which is preferably provided with the annular flange 28 is yieldably forced into contact with the forward end of the abutment 8, but at the same time the movement of the true barrel in either 30 direction is limited by means of the stops 21 and 25. As shown in Figure 3, the rear end of the true barrel 19 is adapted to extend slightly beyond the rear end of the false barrel 20 when the false barrel is in its 35 broken-down position; but as shown in Figure 2, the rear end of the true barrel is substantially flush with the rear end of the false barrel due to being engaged by the abutment 8 when the false barrel is rotated 40 into shooting position. The front face of the abutment is preferably formed of a pliable material such as leather to assure a better seal.

As shown in Figure 4, the annulus 22 has 50 the segmental notch 29 in its periphery to permit of moving the annulus longitudinally into the false barrel 20 and past the portion 26 of the stop 25. The abutment 23 fixedly secured to the true barrel 19 has the hub 55 portion 30 upon the true barrel and the diametrically oppositely extending flat portions 31, one of which is adapted to engage in the U-shaped slot 21 of the stop 25. By reason of this construction, the annulus 22, 60 coil spring 24, abutment 23 and true barrel 19 may be longitudinally inserted into the false barrel 20 and the true barrel then rotated sufficiently to engage the abutment 23 in the U-shaped slot 27.

65 To facilitate the rotation of the true bar-

rel 19 and abutment 23 fixed thereon, the flange 28 has the slot 32 in its rear face to permit of the use of a suitable tool such as a screw-driver.

Another feature of my invention resides 70 in forming the shank connected to the plunger of the gun to facilitate the assembly of the parts. In detail, 33 is a cylindrical shank secured to the plunger 5 and having at its rear end the down-turned portion 17. 75 The coil spring 6 engages within this cylindrical shank.

What I claim as my invention is:

1. In an air gun, the combination with the casing and an abutment therein, provided 80 with an aperture for the passage of air, of a false barrel pivotally connected to said casing, a true barrel in said false barrel adapted to register with said aperture when said false barrel is in alignment with said casing, 85 and yieldable means for sealing the joint between said true barrel and abutment, operated automatically by swinging said false barrel into alignment with said casing.

2. In an air gun, the combination with 90 the casing and an abutment fixed therein and provided with an aperture for the passage of air, of a false barrel pivotally connected to said casing, a true barrel in said false barrel adapted to register with said 95 aperture when said false barrel is in alignment with said casing, and means for yieldably forcing said true barrel rearwardly, said abutment being arranged so that it engages said true barrel upon the swinging of 100 said false barrel into alignment with said casing and forms a seal therewith when said false barrel is in alignment with said casing.

3. In an air gun, the combination with 105 the casing and an abutment fixed therein and provided with an aperture for the passage of air, of a false barrel pivotally connected to said casing, a true barrel removably mounted in said false barrel, means for yieldably forcing said true barrel into contact with said abutment when said false barrel is in alignment with said casing, and stops upon said false barrel for limiting the movement of said true barrel in either direction, one of said stops permitting of removal of said true barrel. 115

4. In an air gun, the combination with the casing and an abutment fixed in the outer end thereof and provided with an aperture for the passage of air, of a false barrel pivotally connected to said casing, a true barrel removably mounted in said false barrel and adapted to register with the aperture in said abutment when said false barrel is in alignment with said casing, a stop upon said false 120 barrel having a portion extending adjacent to the wall thereof with a slot in its forward end, a second stop within said false barrel forward of said member, an abutment 125 upon said true barrel engageable in the slot 130

in said first-mentioned stop, and a coil spring surrounding said true barrel and located between said true barrel abutment, and second stop.

5. In an air gun, the combination with the casing and an abutment fixed in the outer end thereof and provided with an aperture for the passage of air, of a false barrel pivotally connected to said casing, a true barrel 10 insertible into said false barrel and adapted to register with the aperture in said abutment when said false barrel is in alignment with said casing, a sight upon said false barrel having a portion extending within and 15 adjacent to the wall thereof with a slot in its forward end, a second stop within said false barrel, an abutment upon said true barrel having a portion extending radially therefrom and into engagement with the slot in 20 said sight, a coil spring between said stop and abutment and a flange upon said true barrel adapted to abut said abutment in said casing, said flange provided with a recess for facilitating the rotation of the true bar- 25 rel in assembling with the false barrel.

6. In an air gun, the combination with the casing, of a barrel pivotally connected thereto, and means engaging and cooperat- 30 ing with the pivot for holding said barrel in alignment with said casing.

7. In an air gun, the combination with the casing, a plunger therewithin and a spring for actuating said plunger in one direction, of a barrel pivotally connected to said cas- 35 ing, means for compressing said spring upon

rotation of said barrel, and means cooperat- 40 ing with said compressing means for holding said barrel in alignment with said casing.

8. In an air gun, the combination with the casing, a plunger therewithin and a spring for actuating said plunger in one direction, of a barrel pivotally connected to said casing, and a rod connected to said barrel for compressing said spring upon rotation of said barrel, said rod being yield- 45 ably engageable with the pivot between said barrel and casing for holding said barrel in alignment with said casing.

9. In an air gun, the combination with the casing, a plunger therewithin and a spring for actuating said plunger in one direction, of a barrel pivotally connected to said casing, and a U-shaped rod connected to said barrel at its ends for compressing said spring upon swinging of said barrel, said U-shaped rod having substantially parallel arms spaced apart a distance less than the length of the pivot connecting said barrel to said casing and said arms being resilient to snap over the ends of the pivot when swinging said 55 barrel into shooting position.

10. In a gun, the combination with the casing, of a barrel pivotally connected thereto, and a rod pivotally connected to said casing and barrel and yieldably engageable with the pivot between said casing and barrel for holding said barrel in alignment with said casing.

In testimony whereof I affix my signature.
ERNEST S. ROE.
